US0D1033633S

(12) **United States Design Patent** (10) Patent No.: **US D1,033,633 S**
(45) Date of Patent: ** Jul. 2, 2024

(54) **ON-BODY FILLABLE INJECTOR**

(71) Applicant: **Becton, Dickinson and Company**,
Franklin Lakes, NJ (US)

(72) Inventors: **Vincent Delobelle**, Domene (FR);
Eleanor Bainton, Kineton (GB); **James Leslie Rhodri Jones**, Pencader (GB);
Daniel Paul Jenkins, St Albans (GB);
Zoe Georgina Armstrong, Market Drayton (GB); **Malcolm Stanley Boyd**, Wellesbourne (GB)

(73) Assignee: **Becton, Dickinson and Company**,
Franklin Lakes, NJ (US)

(**) Term: **15 Years**

(21) Appl. No.: **29/881,368**

(22) Filed: **Dec. 30, 2022**

(51) LOC (14) Cl. **24-02**

(52) U.S. Cl.

USPC **D24/113**

CLAIM

The ornamental design for an on-body fillable injector, as shown and described.

DESCRIPTION

FIG. 1 is a front perspective view of an on-body fillable injector, showing our new design;

FIG. 2 is a rear perspective view thereof;

FIG. 3 is a front view thereof;

FIG. 4 is a top view thereof;

FIG. 5 is a side view thereof;

FIG. 6 is a side view thereof;

FIG. 7 is a rear view thereof; and,

FIG. 8 is a bottom view thereof.

1 Claim, 7 Drawing Sheets
